LAUNDRY BAG HOLDER

Filed Oct. 12, 1927

UNITED STATES PATENT OFFICE

JOHN DI BERNARDO AND FRANCIS S. MERNE, OF BROOKLYN, NEW YORK

LAUNDRY-BAG HOLDER

Application filed October 12, 1927. Serial No. 225,822.

This invention relates to receptacles and in particular to a type adapted to be positioned in a washing machine to hold the individual laundry bag during the washing 5 operation.

A particular object of our invention is to provide a receptacle in a washing machine in which the laundry bag used to contain the laundry to be washed may be held during the washing operation to be cleansed without becoming entangled in the clothes which are in the main washing machine receptacle.

A further object of our invention is to provide a receptacle which, while maintaining the laundry bag separated from the clothes to be washed, will also prevent the clothes in the washer from being torn by reason of contact therewith and will also be in a convenient position so that the laundry bag may be immediately drawn out of the washing machine before the clothes are removed, so that the bag is ready for receiving the clothes after they have been 25 passed through the extractor.

A still further object of our invention is to provide a laundry bag receptacle which can be conveniently positioned within a laundry machine without altering any of 30 the washer parts and without interfering with the operation thereof.

To enable others skilled in the art to fully comprehend the underlying features of our invention that they may embody the same 35 in the various modifications in structure and relation contemplated, a drawing depicting a preferred form has been annexed as a part of this disclosure and in such drawing similar reference characters denote corresponding parts throughout all the views, of which,

Figure 1 is a view in perspective of a laundry machine of the cylindrical type in which are positioned two revolving inner 45 cylindrical drums each used to contain an individual wash, the door of one of the drums being open to disclose our improved laundry bag receptacle.

Figure 2 is a fragmentary section taken on the line 2-2 of Figure 1, showing the

attachment of our improved laundry bag receptacle to the interior of one of the inner cylindrical drums.

Figure 3 is a view similar to Figure 2 on a smaller scale showing the position the 55 laundry bag receptacle will occupy when the door or cover of the cylindrical drum is closed to maintain the receptacle in position.

Figure 4 is a section taken on the line 4-4 of Figure 3 showing the construction 60 of one side of the receptacle; and

Figure 5 is a fragmentary section taken on the line 5-5 of Figure 3 showing how a locking lip is used to retain the bag 65 receptacle in position.

Referring to the drawing in detail, 5 indicates a washing machine of the cylindrical type which is provided with the covers 6, which are slidable to open the casing of the washing machine so that access may be had to the inner cylindrical drums 7, which are revolvably mounted within the casing of the washing machine 5 and are each used to contain an individual family wash, the drums being also provided with the doors 70 75 8 through the medium of which the wash may be removed therefrom.

Heretofore in the washing of clothes, the laundry bag which was made of canvas or net was thrown in with the clothes for washing and when the clothes were removed, it was found that the laundry bag was all tangled up with the clothes due to the churning action of the washer and in removing the bag from among the clothes, the latter were usually torn because the bag could withstand the pulling given it in removing the clothes, while the clothes being delicate were torn. In order to eliminate this objection, we have provided a receptacle which is adapted to be positioned on the interior surface of the individual inner cylindrical drums adjacent the door thereof so that when the wash has been placed into the 85 cylinder, the bag may be placed in its own receptacle and when the washing has been completed, may be removed to receive the clothes after they have been passed through the extractor, thus eliminating any danger 90

100

of the bag becoming entangled with the clothes during the washing operation.

To carry out this object, we have provided a semi-cylindrical bag receptacle 9 which is perforated as at 10^a and closed at 5 its ends by the end members 10, the upper portions of which form slides 11 by reason of the fact that they are cut out as at 12 at their upper edges to allow passage there- 10 through of guide members 13, which are secured to the inner wall straps of the drum adjacent the ends of the drum and adjacent the end of the bag receptacle and inwardly of the slides 11 formed on the ends of said 15 receptacle, these guide members being provided front and rear with guide bosses 14 through the medium of which the guides are secured to the straps 15 on the inner surface of the individual inner cylindrical drum 7. The bosses are secured to the 20 straps 15 through the medium of bolts 16 and the forward boss 14 is secured to the strap 15 that lies adjacent the hinge 17 of the door 8, this latter being also provided 25 with a reinforcing strip 19, the purpose of which will be hereinafter described. It is apparent from Figure 2 that the guides 13 are positioned on both sides of the wash bag 30 receptacle and the latter through the medium of its guide members, has forward sliding movement in the guides so that when the door 8 is open, the bag holding receptacle will slide forward in the guides 13 to the position shown in Figure 2 at which 35 time the wash bag can be removed therefrom. The guides 13 are provided in their forward portions with the depending lugs 20 which act to limit the forward sliding movement of the bag receptacle by coming 40 into contact with the guides 11 and adjacent the depending lugs 20 there is provided an opening 21 into which drops a lip 22 formed on the guide 11, this lip being for the purpose of preventing forward sliding 45 movement of the wash bag receptacle after the same is moved rearwardly to allow the door 8 to be closed. When the wash bag receptacle 9 has been pushed rearwardly, that is, toward the back of the machine 50 in the guides 13, the extended forward portion 23 of the receptacle will be in position to lie behind the strap 19 of the door 8. In addition to the lip 22 retaining the bag receptacle 9 in its rearward position until the 55 door 8 is closed, the strap 19 on the door will prevent any movement of the bag receptacle during revolving movement of the inner cylindrical drum 7.

It is quite evident that the openings 10 in 60 the wash bag receptacle will allow passage of the water therethrough to cleanse the bag and will also be self-draining when the drum 7 is brought to a stop.

It is also evident that the end of the 65 guides, in which are formed the lugs 20, be-

ing disposed within the drum 7, will abut against the front wall of the bag receptacle 9 and will limit the rearward movement of the receptacle when the same is pushed in the guides 13 to allow the door 8 to be 70 closed. The slides 11 have sufficient play in the guides 13 to permit the lugs 22 of the slides being raised to clear the openings 21.

It is quite evident also, that our improved 75 laundry bag holder may be placed in any machine employing inner cylindrical drums of the revolvable type.

It is apparent also, that we have provided a wash bag receptacle which will permit 80 the bag to be cleansed simultaneously with the clothes but separate therefrom so that the danger of entanglement of the clothes with the wash bag is eliminated.

While we have illustrated and described 85 our invention with some degree of particularity, we realize that in practice various alterations therein may be made. We therefore reserve the right and privilege of changing the form of the details of construction 90 or otherwise altering the arrangement of the correlated parts without departing from the spirit of the invention or the scope of the appended claims.

Having thus described our invention what 95 we claim as new and desire to secure by United States Letters Patent is:—

1. In a washing machine, an inner cylindrical drum having an opening in the curved wall thereof, and a door for closing said 100 opening, a perforated receptacle positioned interiorly of the drum and having an open side opposite the curved wall of the drum and also having a bottom wall and end walls, guides within the drum adjacent the end walls thereof, means upon the end walls of the receptacle slidably engaging the guides whereby to provide for movement of the receptacle into and out of position with its open side registering with the door of the drum, and means for holding the receptacle in such position and in a position with its open side rearwardly with respect to the said door.

2. In a washing machine, an inner cylindrical drum having an opening in its wall, a door for closing said opening, a receptacle positioned within the drum and comprising a perforated semi-cylindrical body having end walls, and an open side, 115 the open side of the body being adjacent the wall of the drum, guides within the drum, means upon the end walls of the receptacle slidably engaging the guides to provide for movement of the receptacle into and 120 out of position with its open side opposite the said opening in the wall of the drum, and coating means upon the receptacle and the said door for holding the receptacle in position with its open side rearwardly of the 130

opening in which the door is mounted, when the door is in closed position, the said means comprising a cleat upon the inner side of the door and an extension from the wall of the receptacle at one side of the open side thereof of engageable with said cleat.

3. In a washing machine, an inner cylindrical drum having an opening in its wall, a door for closing said opening, a receptacle positioned within the drum and comprising a perforated semi-cylindrical body having end walls, and an open side, the open side of the body being adjacent the wall of the drum, guides within the drum, means upon the end walls of the receptacle slidably engaging the guides to provide for movement of the receptacle into and out of position with its open side opposite the said opening in the wall of the drum, and coacting means upon the receptacle and the said door for holding the receptacle in position with its open side rearwardly of the opening in which the door is mounted, when the door is in closed position, the said means including a cleat upon the inner side of the door, an extension upon the body wall of the receptacle engageable with said cleat when the door is in closed position, and coacting means upon the receptacle and the guides for holding the receptacle in position with the extension of its said wall in position to be engaged by the said cleat when the door is closed.

In testimony whereof we affix our signatures.

JOHN DI BERNARDO. [L. S.]
